DESIGN FOR A COSMETIC TRAY

Elaine M. Malco, Long Beach, Calif.

Application August 12, 1946, Serial No. 132,448

Term of patent 3½ years

(Cl. D86—10)

To all whom it may concern:

Be it known that I, Elaine M. Malco, a citizen of the United States and a resident of Long Beach, county of Los Angeles, and State of California, have invented a new, original, and ornamental Design for a Cosmetic Tray, of which the following is a specification, reference being had to the accompanying drawing, forming a part thereof.

The figure in the drawing is a perspective view of a cosmetic tray showing my new design.

I claim:

The ornamental design for a cosmetic tray, as shown,

ELAINE M. MALCO.
